A. C. ANDREASEN

PUMP

Filed Jan. 21, 1927.

Inventor

Alfred Cornelius Andreasen

By Clarence A. O'Brien
Attorney

Patented June 5, 1928.

UNITED STATES PATENT OFFICE.

ALFRED C. ANDREASEN, OF CHICAGO, ILLINOIS.

PUMP.

REISSUED

Application filed January 21, 1927. Serial No. 162,518.

The present invention relates to a pump particularly adapted for use with barrels and like containers for forcing liquid therefrom.

5 Another important object of the invention lies in the provision of a pump for use with vessels containing liquid so that pressure may be created above the liquid to force the liquid from the vessel and means whereby 10 the pressure may be released when desired.

A still further important object of the invention lies in the provision of a pumping mechanism that is exceedingly simple in its construction, inexpensive to manufacture, 15 strong and durable, thoroughly reliable and efficient in operation, and otherwise well adapted to the purpose for which it is designed.

With the above and other objects in view, 20 as will appear as the description proceeds, the invention resides in certain novel features of construction, and in the combination and arrangement of parts as will be hereinafter more fully described and 25 claimed.

In the drawing:—

Figure 1 is a sectional view of the pump embodying the features of my invention and showing the same associated with a vessel 30 containing fluid,

Fig. 2 is an enlarged detail sectional view through the pump showing the air pressure release.

Referring to the drawing in detail it will 35 be seen that 5 denotes a vessel in the form of a tank having a threaded opening 6 in the top thereof. This tank is clearly shown by way of example and does not form a part of the invention. The tank contains liquid as is indicated at 7.

Referring to the pumping mechanism in detail it will be seen that the numeral 8 denotes the cylinder the lower end of which is open and the upper end of which is closed 45 as at 9 and has a stuffing box 10 in the center thereof. A head or cap 11 is threadedly engaged as at 12 on the lower openings of the cylinder 8 and has a central opening 13.

A tubular member 14 extends from the head 50 or cap 11 and is reduced intermediate its ends to form a shoulder 15 and an externally threaded portion 16 adapted to be engaged with the threaded opening 6. A pipe 17 depends from the portion 16 and is 55 adapted to terminate in close proximity to the bottom of the tank 5. An outlet pipe 18

extends from the tubular portion 14 laterally thereof so that the hose or the like may be connected therewith for leading the liquid pumped from the tank to any desired 60 place. A pipe 19 depends downwardly from the central portion of the head or cap 11 through the tubular member 14 and has its lower end bent laterally to extend through an opening 20 in the portion 16. A spring 65 pressed check valve is mounted in the pipe 19 to normally close the opening 13.

The numeral 23 denotes a hollow plunger rod 70 slidable through the stuffing box 10 and having a flexible plunger 24 mounted on its inner lower end in abutment with the bracing disk 25 which is smaller in diameter than the plunger. The upper portion of the cylinder is provided with a vent opening 26. 75 The upper outer end of the plunger rod 23 has a bracket 27 mounted thereon and pivotally engaged with the lever 28. A rod 29 is pivotally engaged as at 30 with one end of the lever 28 and the other end is pivotally engaged as at 31 with the bottom of the cap 80 11. A spigot 32 is mounted on the upper end of the hollow plunger rod 23. A spider 33 is mounted in the lower end of the hollow plunger rod 23 as is clearly shown in Fig. 2 85 and has a pin 34 projecting therefrom below the lower end of said rod, so that when the plunger is in its normal position said pin 34 will engage the check valve 21 and release it from the opening 13 to leave any air pressure in the top of the tank 5 through 90 the pipe 19.

When the lever 28 is actuated to force the plunger 24 downwardly it will be seen that air is driven through the opening 13 causing the valve 21 to open so that the air will flow 95 through the pipe 19 into the top of the tank to set up a pressure therein. As the lever is swung upwardly the plunger 24 moves upwardly and said plunger will flex to allow air to escape thereby into the lower portion 100 of the cylinder 8 as will be quite apparent. Thus the setting up of a rectilinear motion of the plunger will cause the creation of a head of pressure in the top of the tank bar so that the oil or like fluid 7 therein will be forced up the extension 17, through the portion 16, through the member 14 out through the pipe 18. If, for any reason, it is desired 105 to release the pressure in the tank, it is only necessary to move the plunger to the bottom of the cylinder so that the pin 24 unseats the valve 21 and then open to the spigot 32. 110

It is thought that the construction, operation and advantages of the invention will now be clearly understood without a more detailed description thereof.

5 The present embodiment of the invention has been disclosed in detail merely by way of example since in actual practice it attains the features of advantage enumerated as desirable in the statement of the invention and 10 the above description. It will be apparent that the changes in the details of construction, and in the combination and arrangement of parts may be resorted to without departing from the spirit or scope of the invention as hereinafter claimed or sacrificing any of its advantages.

Having thus described my invention, what I claim as new is:

In a pumping mechanism of the class de-

scribed, the combination of a cylinder, a 20 plunger slidable in the cylinder, a hollow plunger rod connected with the plunger and extending through one end of the cylinder to terminate exteriorly thereof, means for reciprocating the hollow rod, a manually 25 operable valve at the outer end of the hollow plunger rod, a check valve in the other end of the cylinder, a pin extending from the plunger in an opposite direction to the rod to engage the check valve for unseating the 30 same when the plunger approaches the check valve closely so that the manually operated valve may be opened to allow a vent passage therethrough and through the hollow plunger rod and the check valve.

85
In testimony whereof I affix my signature.

ALFRED C. ANDREASEN.
